UNITED STATES PATENT OFFICE.

WILLIAM G. LINDEMANN, OF MILWAUKEE, WISCONSIN.

ELECTRIC-LAMP SOCKET.

1,086,543.

Specification of Letters Patent. Patented Feb. 10, 1914.

Application filed June 2, 1913. Serial No. 771,160.

To all whom it may concern:

Be it known that I, WILLIAM G. LINDEMANN, a citizen of the United States, residing at Milwaukee, in the county of Milwaukee and State of Wisconsin, have invented new and useful Improvements in Electric-Lamp Sockets, of which the following is a specification, reference being had to the accompanying drawing, forming a part thereof.

This invention relates more particularly to the metal casing or housing of the socket, and is applicable to keyless sockets as well as to sockets provided with key or other switches for turning on and off the light.

The main objects of the invention are to facilitate access to interior parts of the socket, such as the cord or wire connections and the switch mechanism, if present, without disturbing the shade holder, switch key or attachment of the socket to an electrolier or other fixture, especially an ornamental or other fixture in which such attachment is not easily accessible; and generally to improve the construction of lamp sockets of this class.

It consists in the construction, arrangement and combination of parts as hereinafter particularly described and pointed out in the appended claims.

In the accompanying drawing like characters designate the same parts in the several figures.

Figure 1 is a side elevation of a lamp socket embodying the invention, with a lamp inserted therein; Fig. 2 is an axial section of the socket; Fig. 3 is a view of the upper or larger end of the body of the socket housing; Fig. 4 is an inverted plan view of the housing cap; Fig. 5 is a side elevation of the upper portion of the body of the housing; and Fig. 6 is an axial section of portions of the separable body and cap of the housing.

The housing or casing of the socket consists of two separable parts or sections, a cylindrical body *a*, and a cap *b*, which are preferably made of sheet metal, such as brass. The body part or section *a*, has a larger end portion for the reception of an insulating block or head *c* of the usual or any suitable construction, and a smaller end portion for the reception of a threaded

lamp holder *d*, which is attached to the block *c* and is of the usual or any suitable construction. The lower or smaller end of the body *a* has a screwthread pressed therein, and above the screwthread is formed with a bead *e*. At its upper or larger end the body *a* is formed, as shown most clearly in Figs. 3, 5 and 6, with angular or laterally and reversely offset slots *f*, having closed ends *g*, as shown in Fig. 5. These slots are preferably pressed into and not cut through, the sheet metal. The cap *a*, formed with a cylindrical rim fitting over the upper or larger end of the body *b*, is provided on the inside of the rim with lugs *h*, as shown in Figs. 4 and 6, adapted to enter and engage with the slots *f*. The cap is also formed or provided with a neck *i*, in which an insulating bushing *j* is threaded. When the socket is attached to an electrolier or other fixture, the bushing *j* is extended and fastened thereto so as to support the socket in the usual manner. The cord *k* or wires by which the lamp is supplied with current, passes loosely through this bushing and is connected with the contact pieces with which the insulating block *c* is provided, in the usual or any suitable manner. The cap is also provided with an insulating lining, *l*, conforming therewith in shape and having an outwardly flanged margin corresponding with the offset or shoulder between the rounded portion of the cap and its cylindrical rim, as shown in Fig. 2.

A cylindrical insulating lining *m*, inserted between the body *a* of the housing and the block *c*, is inwardly flanged at its upper end over the upper end of the block, to hold it in place thereon, as shown in Fig. 2.

A cylindrical locking sleeve *n*, threaded in the lower or smaller end of the body *a*, is adapted when screwed into place therein, to bear at its upper end against the lower end of the block *c*, and to press it upwardly against the cap *b* or its lining, and thereby confine the lugs *h* of the cap in the upwardly offset ends *g* of the slots *f* in the body *a* and lock the parts of the housing securely together, as shown in Figs. 2 and 6.

The socket is shown in Fig. 2 as provided with a snap switch for turning off and on the current which supplies the lamp. This

switch may be of the usual or any suitable construction for the purpose, and comprises, as shown in Fig. 2, a rotary metal head *o* and spring contact pieces *p* and *q* inclosed in 5 said block, which is recessed and made in two parts or sections to admit of assembling the parts of the switch. The stem *r* of the switch head *o*, which has a bearing in the head *c* and projects laterally therefrom, is 10 provided at its outer end with a key *s*, or other means for turning it.

The body *a* of the housing is notched or slotted at *t*, and the lining *m* is correspondingly but reversely notched or slotted to 15 pass over the shank of the key *s* or switch stem, thereby avoiding the necessity of removing the key or operating connection of the switch when the parts of the housing are separated and the block *c* is removed 20 therefrom.

A cylindrical insulating sleeve *u*, interposed between the lamp holder *d* and locking sleeve *n*, is inwardly flanged at its upper end and clamped between said holder 25 and the block *c* to which it is attached, as shown in Fig. 2.

A shade-holder *v*, preferably formed as shown, of sheet metal, with an internally threaded flange or collar fitting the thread 30 on the smaller end of the body *a*, is screwed firmly against the bead *e*, which serves to limit and lock it in place.

To obtain access to the internal parts of the socket, the lamp being removed, the 35 locking sleeve *n*, the lower end of which projects slightly below the lower end of the body *a* and is formed with a knurled rim, is unscrewed sufficiently to release the block *c* and permit the body and cap *b* to be 40 moved axially toward each other far enough to allow the lugs *h* on the cap to pass out of engagement with the offset ends *g* of the slots *f*. One part of the housing is then turned relative to the other, till the lugs *h* 45 register with the open ends of the slots *f*, whereupon the body is released and withdrawn from the cap, the cord *k* having sufficient slack to permit the separation of the parts and the withdrawal of the block *c* 50 clear from the cap.

When the body *a* is detached from the cap it is free to be withdrawn from the block *c*, which is thus exposed with the cord connections attached thereto, and may be readily 55 taken apart to gain access to the switch. The socket is as readily reassembled by a reversal of the above mentioned operations, the sleeve *u* being finally screwed into the body *a* against the block *c*, to lock and hold the lugs *h* in the offset ends *g* of the slots *f*. Access is thus had to the internal parts of the 60 socket without removing the shade holder from the housing and without disturbing the attachment of the cap *b* to an electrolier

or other fixture, or removing the key *s* or 65 other operating connection of the switch, when the socket is provided with a switch.

While the locking sleeve *n* may be used under all conditions in a lamp socket of the class herein shown and described to secure 70 and hold the parts of the housing together in the proper relation to each other, it is specially designed for, and is of particular advantage in connection with, chandeliers, or fixtures having husks or ornamental covers in which the lamp sockets are inclosed and inaccessible.

I claim:

1. In an electric lamp socket the combination with an insulating block provided with cord connections and a lamp holder, of a housing for inclosing said block and connections comprising two separable parts, a body and a cap, one having laterally and reversely offset slots in one end and the other 85 having lugs adapted to engage said slots, and a locking sleeve threaded in the body of the housing and abutting against one end of said block, the other end of which bears against said cap.

2. In an electric lamp socket the combination with an insulating block provided with cord connections and a lamp holder, of a housing therefor composed of two separable parts, a body having an enlarged end 90 for the reception of said block and a cap fitting over the larger end of the body and provided with an opening for the cord, one of said parts having laterally and reversely offset slots and the other having lugs adapted to engage said slots, and a sleeve threaded in the smaller end of said body and abutting against one end of said block, the other end of which bears against said cap.

3. In an electric lamp socket the combination with an insulating block provided with cord connections and a lamp holder, of a housing therefor composed of two separable parts, a body having a larger end for the reception of said block and a smaller 110 end for the reception of the lamp holder, and a cap fitting over the larger end of the body, one of said parts having laterally and reversely offset slots and the other having lugs adapted to engage said slots, a locking 115 sleeve threaded in the smaller end of said body and abutting against one end of said block, the other end of which bears against said cap, and an insulating sleeve interposed between said locking sleeve and the lamp 120 holder.

4. In an electric lamp socket the combination with an insulating block provided with a lamp holder, switch and cord connections, of a metallic housing therefor composed of two separable parts, a body having a larger end for the reception of said block and a smaller end for the reception of the

lamp holder, the larger end being slotted to pass over the switch stem, and a cap fitting over the larger end of the body, one of said parts being formed with laterally and reversely offset slots and the other with lugs adapted to engage said slots, and a locking sleeve threaded in the smaller end of said

body and abutting against one end of said block, the other end of which bears against said cap.

WILLIAM G. LINDEMANN.
